UNITED STATES PATENT OFFICE.

JOHN A. BALL, OF GRASS VALLEY, CALIFORNIA.

PLOW.

SPECIFICATION forming part of Letters Patent No. 352,849, dated November 16, 1886.

Application filed September 15, 1884. Serial No. 143,103. (No model.)

To all whom it may concern:

Be it known that I, JOHN A. BALL, of Grass Valley, county of Nevada, State of California, have invented an Improvement in Plows, of 5 which the following description, in connection with the accompanying drawings, is a specification, like letters on the drawings representing like parts.

This invention relates to that class of plows 10 known as "reversible," and has for its object the production of a reversible plow in which the mold-board is made concaved and so pivoted as to be readily turned, so that its concaved side will occupy a like position at either 15 side of the beam at will, the said mold-board having attached to or forming a part of it a lay or share which is double pointed. The mold-board herein shown is mounted to turn on a vertical pivot, and I have provided a 20 locking device, which, when moved to release the mold-board, the plow being moved forward in the land, will be automatically shifted to reverse the throwing of the sod, and the action 25 will be the same, no matter whether the mold-board is at the right or at the left hand side of the beam.

Figure 1 in side elevation represents a plow embodying my invention; Fig. 2, a top or plan view of Fig. 1, the dotted line showing the 30 mold-board reversed. Fig. 3 is a section of Fig. 1 on the dotted line $x-x'$. Fig. 4 is a top view of the mold-board and its attached lay or share. Fig. 5 is a horizontal section of the mold-board just above the lower guide-eye; 35 and Fig. 6 is a section of Fig. 4 on the line x^2-x^2' .

The beam A and the handles B are and may be of any usual construction. The beam has bolted to its under side a suitable bearing, C. 40 A bolt, D, is entered, as shown, from below, up through a shoe, E, thence through the eyes 2 3, suitably attached to the concaved mold-board F, and thence through the bearing C and beam A, where the bolt has applied to it a 45 washer, 4, and nut 5.

In practice I prefer to fit into the hollow center of the shoe a thick or square washer, a, and between the said bearing and washer, and extended preferably through the eyes 2 and 3 50 is a sleeve-like collar, b. The eyes 2 and 3 are shown as bolted to the mold-board between its upper and lower edges, and at the center of its

length, and at or near its ends the said mold-board has two other eyes, 6 7, which form part of the mold-board locking device, to be de- 55 scribed.

The concaved mold-board has a lay or share, G, suitably attached to or forming a part of it, the said lay or share having points 8 at each end, either of which may be turned to the 60 front and constitute the point for the plow.

The plow represented in Figs. 1 and 2 in full lines is supposed to be ready to cut and turn a right-hand furrow, but by turning the mold-board and its attached parts into the 65 dotted-line position the furrow will be turned to the left, which provision it is obvious will enable the furrows to be laid in the same general direction in the movement of the plow back and forth.

To hold the mold-board in place I have provided a locking device (shown as a hand-lever, H,) pivoted at 10 on an ear of the bearing C, the said handle-lever having suitable prongs, h, one for each of the eyes 6 7 of the mold- 75 board.

In Figs. 1 and 2 the eye 7 is entered to hold the mold-board, as in full lines. To reverse the mold-board it is only necessary to lift the hand-lever H and remove the prong h from the eye engaged by it, and thereafter any forward movement of the plow, accompanied by a slight side tip toward the land side will, through the pressure of the land against the then forward point, cause the mold-board to 85 turn on its vertical pivot, thus reversing the latter, and properly reversed the handle will be dropped to enable the prong h next the then rear end of the mold-board to enter the eye nearest it, to thus lock the mold-board in place 90 until it is again desired to reverse the same.

The shoe E has substantially straight sides, and is of such width that one or the other side may follow in the line of and form a practical continuation of the landside from the point 95 of the plow.

It will be noticed that the point of the lay or share of my improved mold-board is so shaped and constructed as to always occupy a position at one side of the center of the beam, 100 to thus equalize the draft.

I claim—

1. The plow-beam A and its attached bearing C, combined with the shoe E, having a

squared washer, *a*, fitted therein and held in alignment with the landside or share, the bolt *D*, connecting the beam, bearing, shoe, and washer, and the reversible mold-board secured 5 to the bolt between the washer and bearing by eyes engaging a sleeve on said bolt, and means to lock the mold-board in its positions, substantially as described.

2. The plow-beam having a bearing, *C*, the 10 shoe *E*, the bolt *D*, and its sleeve *b*, combined with the reversible mold-board having eyes at

its center which encircle the sleeve and eyes 6 and 7, as described, and the hand-lever pivoted to the said bearing and provided with the prongs *h*, substantially as set forth. 15

In testimony whereof I have signed my name to this specification in the presence of two subscribing witnesses.

JOHN A. BALL.
